UNITED STATES PATENT OFFICE.

LUCIUS FREEMAN LITTLE, OF OWENSBORO, KENTUCKY, ASSIGNOR TO THE ANGLO-AMERICAN MILL CO., OF OWENSBORO, KENTUCKY, A CORPORATION OF KENTUCKY.

ROLLER-MILL.

1,239,707.

Specification of Letters Patent. Patented Sept. 11, 1917.

Application filed March 1, 1915. Serial No. 11,266.

To all whom it may concern:

Be it known that I, LUCIUS FREEMAN LITTLE, a citizen of the United States, residing at Owensboro, in the county of 5 Daviess and State of Kentucky, have invented new and useful Improvements in Roller-Mills, of which the following is a specification.

The present invention relates to mills, 10 and particularly that type known as roller mills, which are characterized by breaks for initially comminuting the grain; bolting reels or dressers for bolting out the flour or finished product from the stock; and reduction rolls which further reduce the stock, 15 so that the finished product, namely, the flour, and the residue or tailings are finally delivered from the mill in proper condition, the mill being of the self-contained type 20 with the breaking, reducing, and bolting instrumentalities all housed within the mill casing, and so related as that they will take the grain from the hopper, break, reduce, and bolt it, and deliver the finished product.

25 The present invention has to do with means for so handling the stock, and particularly the fine middlings from the bolting reels, that the transfer of the stock from one to the other of the various instrumentalities 30 for reducing it will be facilitated and increase the efficiency and output of the mill; this being accomplished by so routing the stock through the mill and the milling instrumentalities as to reduce to a considerable extent the period of reduction of a given amount of grain.

In the drawings which accompany and form a part of this specification, I have illustrated one embodiment of my invention, 40 and in said drawings—

Figure 1 is a vertical sectional view of a roller mill constructed in accordance with my invention.

Fig. 2 is a vertical section of the mill on 45 the line 3—3, Fig. 1.

Fig. 3 is a vertical section of the mill on the line 2—2, Fig. 1.

Referring to the drawings by numbers, like numbers indicating like parts in the 50 several views, 10 indicates the mill frame or housing within which are placed the breaking, reducing, and bolting instrumentalities, any suitable drive mechanism for imparting motion to the breaks, reduction rolls, centrifugal dressers, and con-

veyers being provided. The first break 11 consists of any suitable breaking rolls, into which the grain will be fed from any suitable feeding device or hopper 12.

The broken or comminuted grain is delivered from the break rolls 11 to a shaking screen or scalper 13, which screens out the fine stock and delivers it to a conveyer 14 which carries it to a bolting reel having a fine mesh dressing section 15, and a coarse 60 mesh dressing section 16, the two being divided by a suitable partition 17. In the bolting reel the flour is dressed out of the fine mesh section 15, while in the coarse mesh section 16 the fine middlings are 65 dressed out, the residue or coarse middlings tailing over to a suitable chute 18, through which they are delivered to a conveyer 19 and carried to the first reduction rolls 20, from which they are carried by a conveyer 70 75 operating in a suitable trough to the centrifugal dresser 21 for the first reduction rolls, the flour is bolted out, and the scalped middlings fall to a conveyer presently to be described. The trough 50 in which the conveyer 19 is located terminates in a hopper 51 which delivers to the reduction rolls 20.

The stock which passes over the screen 13 falls to a suitable feed plate 22, and thence to a second break 23, where it is further reduced, and by a conveyer 24 is delivered to a second bolting reel 25, which dresses out the flour, the fine middlings and the coarse middlings, and delivers the tailings, which are finished broad bran, to a spout 90 by which they are delivered to the sacking point.

The fine middlings from the fine grits gauze section 16 of the first bolting reel are delivered to a receptacle 26, from which 95 they are swept by the blade 27 to a feed board 28, down which they pass to a second feed board 29, and thence to the conveyer 30, by which they are carried across to an elevator 31 which lifts the middlings to a 100 delivery spout 32 leading to a hopper 49 delivering to the second reduction rolls 33, so that the fine middlings pass directly from the first bolting reel to the second reduction rolls.

105 The bolting reel 25 for the second break 23 is provided with a fine middlings receptacle 34, which extends over a relatively short section of the grits gauze portion of the reel, which section is of relatively fine 110

grits gauze and is adjacent the flour dressing section, as shown in Fig. 1, so that as the stock passes from the flour dressing section to the middlings section, such fine middlings as remain in the stock coming from the second break 23 will be delivered to the fine middlings receptacle 34, from which, as shown in Fig. 2, the sweeper 35 on the centrifugal dresser will sweep the fine middlings and deliver them over the top of the coarse middlings conveyer 19, over which the receptacle 34 arches, through the aperture in the feed board 36, from which they will fall to the feed board 29 and be delivered to the conveyer 30, together with the fine middlings from the bolting reel for the first break, hereinbefore described, and by the conveyer 30 delivered to the elevator 31 and thence to the second reduction rolls. 20 The bolting reel 25 has at its extreme end a section of relatively coarse grits gauze which bolts out the coarse middlings and these fall into the conveyer 19 and pass to the first reduction rolls, with the overtails 25 coming from the dresser 16 by the spout 18, as hereinbefore described.

It will be seen from the foregoing that the bolting reels for the first and second breaks and the first reduction rolls take out the flour from the stock and deliver the fine middlings directly to the conveyer 30, which, in turn carries them to the elevator 31 by which they are sent to the second reduction rolls 33, from which they are carried by a conveyer 48 operating in a suitable trough to the centrifugal dresser 46 for the second reduction rolls, which dresses out the flour in the flour section and delivers it to the flour hopper 38, the cut-off section of this reel being arranged so a second grade flour may be taken off and spouted direct to the bagging point, the shorts or "finish" being tailed out of the reel. 40

In order to adapt the mill for a different routing of the stock from that just described, if this should be found desirable, I preferably hinge the feed board 36 so that it may be swung to the position shown in dotted lines in Fig. 2, a latch or stop 41 being provided to maintain it in this position, while the latch 42 holds it in its uppermost position (full lines Fig. 2).

When in the position shown in dotted lines in Fig. 2, the fine middlings coming 55 from the first break dresser 16 over the feed board 28 will be directed to the conveyer 19 and by it delivered to the first reduction rolls instead of passing to the conveyer 30, as hereinbefore described. The board 36 60 when in the position shown in dotted lines will have its aperture through which the middlings from the second break pass, when it is in position for routing the flour as above described, closed by means of a small 65 gate 43 pivotally mounted on the board and

having a latch 44 by means of which it may be secured, this gate 43, when the board 36 is in the full line position shown in Fig. 2, hanging in the vertical position shown. When the board 36 is in the dotted line position for delivering middlings to the conveyer 19, the arched portion 45 of the receptacle 34 will be removed so as to open the conveyer throughout its entire length, this arched portion being separable from the rest 70 of the receptacle so that it may be readily inserted or placed in position to adapt the mill to the different routing of the material. From the first reduction rolls the middlings will then pass to the dresser 21 for the first 75 reduction rolls, where they will be bolted and the middlings will be delivered to conveyer 30, and by it carried to elevator 31 which will deliver them to the second reduction rolls and its dresser for final grinding and dressing. 80

In a mill constructed in accordance with this disclosure, a better grading of middlings is secured and a material saving in time is effected by routing the stock so as to take the fine middlings from the breaks direct to suitable reduction rolls and eliminating unnecessary handling of them after they have been once brought to proper condition for treatment by the rolls. It results 95 not only in shortening the period of time within which a given quantity of grain may be milled, but the better graded middlings also insures a maximum amount of flour. 90

Various changes in mechanical structure 100 may be made without departing from the principle of my invention.

I claim:—

1. In a mill, the combination of a pair of break rolls, a centrifugal dresser to receive the product from said break rolls and dress out the flour and the fine middlings, first and second sets of reduction rolls, means to deliver the fine middlings directly to one set of reduction rolls, and means to 105 deliver the coarse middlings to the other set and then to said first set of reduction rolls. 110

2. In a mill, the combination of a pair of break rolls, a centrifugal dresser to receive the product from said break rolls and dress out the flour and the fine middlings, a second set of break rolls, means to deliver part of the product to said centrifugal dresser and the overtails from said first 115 break to said second break, a centrifugal dresser to receive the product from said second set of break rolls and dress out the flour and the fine middlings, two sets of reduction rolls, means to deliver the fine middlings from the dressers for the first and second breaks directly to one set of reduction rolls, and means to deliver the coarse middlings to the other set. 120

3. In a mill, the combination of a pair 125

of break rolls, a centrifugal dresser to receive the product from said break rolls and dress out the flour and the fine middlings, a conveyer to which the fine middlings are delivered, a second set of break rolls, means to deliver part of the product to said centrifugal dresser and the overtails of said first break to said second break, a centrifugal dresser to receive the product from said 5 second set of break rolls and dress out the flour and the fine middlings and deliver said fine middlings to said conveyer, two sets of reduction rolls, means to which said conveyer delivers to carry the fine middlings directly to one set of reduction rolls, and means to deliver the coarse middlings to the other set.

4. In a mill, the combination of a pair of break rolls, a centrifugal dresser to receive the product from said break rolls and dress out the flour and the fine middlings, a conveyer to which the fine middlings are delivered, a second set of break rolls, means to deliver part of the product to said 20 centrifugal dresser and the overtails of said first break to the second break, a centrifugal dresser to receive the product from said second set of break rolls and dress out the flour and the fine middlings and deliver 25 said fine middlings to said conveyer, two sets of reduction rolls, means to which said conveyer delivers to carry the fine middlings directly to one set of reduction rolls, and means to deliver the coarse middlings to the 30 other set.

5. In a mill, the combination of a pair of break rolls, a centrifugal dresser to receive the product of said break rolls and dress out the flour and the fine middlings, a second pair of break rolls, means to deliver part of the product from said first pair of break rolls to said centrifugal dresser and the overtails from said first break to said 40 second break, a centrifugal dresser to receive the product from said second pair of break rolls and dress out the flour and the fine middlings, a conveyer which receives the coarse middlings from said centrifugal dresser, a set of reduction rolls to which 45 said conveyer delivers, a centrifugal dresser for said reduction rolls to dress out the flour and the fine middlings, and conveying means for said fine middlings to which said centrifugal dressers deliver which carries the 50 fine middlings directly to a second set of reduction rolls.

6. In a mill, the combination of a pair of break rolls; a centrifugal dresser to receive the product from said break rolls, dress out 55 the flour and the fine middlings and deliver the overtails to a suitable conveyer; a second pair of break rolls, means to deliver part of the product from said first pair of break rolls to said centrifugal dresser and the overtails from said first break to said

second break; a centrifugal dresser to receive the product from said second pair of break rolls, said dresser having a flour-producing section, a fine middlings section and a coarse middlings section; a set of second 70 reduction rolls; a conveyer to which the fine middlings sections of said centrifugal dressers deliver to carry the fine middlings directly to said second reduction rolls; a set of first reduction rolls; means for conveying the coarse middlings from the first and second break dressers to said set of first reduction rolls; and a centrifugal dresser to receive the product from said set of first reduction rolls, dress out the flour and deliver the fine middlings to said first-named 75 conveyer.

7. In a mill, the combination of two pairs of break rolls, a centrifugal dresser for each pair of break rolls and each of which has a flour-producing section, means to deliver the product from the first pair of break rolls to the centrifugal dresser for said pair of break rolls and the overtails to the second set of break rolls for the second 80 centrifugal dresser and a fine middlings producing section, two sets of reduction rolls, conveying means to deliver the fine middlings from said dressers directly to the second set of reduction rolls, conveying 85 means to deliver the overtails of said dressers to the first set of reduction rolls, and a centrifugal dresser for each of said reduction rolls.

8. In a mill, the combination of two pairs of break rolls, a centrifugal dresser for each pair of break rolls and each of which has a flour-producing section and a fine middlings producing section, means to deliver part of the product from the first set of break rolls 100 to the centrifugal dresser therefor and the overtails to the second set of break rolls, two sets of reduction rolls, conveying means common to both of said dressers to receive the fine middlings and deliver them directly 105 to the second set of reduction rolls, and conveying means common to both dressers to receive and deliver the coarse middlings 110 to the first set of reduction rolls.

9. In a mill, the combination of two pairs of break rolls, a centrifugal dresser for each pair of break rolls and each of which has a flour-producing section and a fine middlings producing section, means to deliver part of the product from the first pair of break rolls to the centrifugal dresser therefor and the overtails to the second set of breaks, two sets of reduction rolls, conveying means common to both of said dressers to receive the fine middlings and deliver 115 them directly to the second set of reduction rolls, conveying means common to both dressers to receive and deliver the coarse middlings to the first set of reduction rolls, and a centrifugal dresser to receive the 120 125 130

product from said second set of reduction rolls.

10. In a mill, the combination with a plurality of break rolls, and a plurality of reduction rolls, of a plurality of centrifugal dressers to dress out the flour and middlings in the stock coming from said rolls, a conveyer to receive the fine middlings from the dressers and deliver them directly to a predetermined point, and conveying means to deliver the coarse middlings from said dressers to another predetermined point without mixing the said fine and coarse middlings.

15 11. In a mill, the combination of two pairs of break rolls, means to deliver the overtails from one pair of breaks to the other pair, a centrifugal dresser for each pair of rolls, a fine middlings conveyer,
20 means for delivering the fine middlings from said dressers to said conveyer, two sets of reduction rolls, an elevator which takes the fine middlings from said middlings conveyer and directly delivers it through a
25 suitable feed spout to a set of reduction rolls, and a conveyer which takes the overtails from said dressers and delivers them to the other set of said reduction rolls and then to the first-mentioned set of rolls.

30 12. In a mill, the combination of a pair of
break rolls, a centrifugal dresser to receive
the product of said rolls, a series of feed
boards to deliver the fine middlings from
said dresser to a middlings conveyer, a sec-
35 ond pair of break rolls, means to deliver the
overtails from the first pair of break rolls to
the second pair of break rolls, a centrifugal
dresser for said rolls, a middlings conveyer
for said second dresser to receive the coarse
40 middlings, and means for delivering the fine
middlings from said second break dresser to
the fine middlings conveyer for the first
break dresser.

13. In a mill, the combination of a pair of
45 break rolls, a centrifugal dresser to receive
the product of said rolls, a series of feed
boards to deliver the fine middlings from
said dresser to a middlings conveyer, a sec-
ond pair of break rolls, means to deliver the
50 overtails from the first pair of breaks to the
second pair of breaks, a centrifugal dresser
for said rolls, a middlings conveyer for said
second dresser to receive the coarse mid-
dlings, and means for delivering the fine
55 middlings from said second break dresser to
the fine middlings conveyer for the first
break dresser comprising a feed board cov-
ering a portion of the middlings conveyer
for the second break dresser.

60 14. In a mill, the combination of a pair of break rolls, a centrifugal dresser to receive the product of said rolls, a series of feed boards to deliver the fine middlings from said dresser to a middlings conveyer, a second pair of break rolls, means to deliver the

65

overtails from the first pair of breaks to the second pair of breaks, a centrifugal dresser for said rolls, a middlings conveyer for said second dresser to receive the coarse middlings, and means for delivering the fine 70 middlings from said second break dresser to the fine middlings conveyer for the first break dresser comprising an arched feed board covering a portion of the middlings conveyer for the second break dresser. 75

15. In a mill, the combination of a pair of break rolls, a centrifugal dresser to receive the product of said rolls, a series of feed boards to deliver the fine middlings from said dresser to a middlings conveyer, a second pair of break rolls, means to deliver the overtails from the first pair of breaks to the second pair of breaks, a centrifugal dresser for said rolls, a middlings conveyer for said second dresser to receive the coarse middlings, and means for delivering the fine middlings from said second break dresser to the fine middlings conveyer for the first break dresser comprising a removable arched feed board covering a portion of the middlings conveyer for the second break dresser.

16. In a mill, the combination of a pair of break rolls, a centrifugal dresser to receive the product of said rolls, a series of feed boards to deliver the fine middlings from said dresser to a middlings conveyer, a second pair of break rolls, means to deliver the overtails from the first pair of breaks to the second pair of breaks, a centrifugal dresser for said rolls, a middlings conveyer for said second break dresser to receive the coarse middlings, means for delivering the fine middlings from said second break dresser to the fine middlings conveyer for the first break dresser, and means to interrupt the flow from said first break dresser and direct it to the conveyer for said second break dresser when desired. 95 100 105

17. In a mill, the combination of a pair of break rolls, a centrifugal dresser to receive the product of said rolls, a series of feed boards to deliver the fine middlings from said dresser to a middlings conveyer, a second pair of break rolls, means to deliver the overtails from the first pair of breaks to the second pair of breaks, a centrifugal dresser for said rolls, a middlings conveyer for said second break dresser to receive the coarse middlings, means for delivering the fine middlings from said second break dresser to the fine middlings conveyer for the first break dresser, and means comprising a hinged feed board to interrupt the flow from said first break dresser and direct it to the conveyer for said second break dresser when desired. 110 115 120 125

18. In a mill, the combination of a pair of break rolls, a centrifugal dresser to receive the product of said rolls, a series of 130

- feed-boards to deliver the fine middlings from said dresser to a middlings conveyer, a second pair of break rolls, means to deliver the overtails from the first pair of breaks to the second pair of breaks, a centrifugal dresser for said rolls, a middlings conveyer for said second break dresser to receive the coarse middlings, and means for delivering the fine middlings from said second break 5 dresser to the fine middlings conveyer for the first break dresser, one of the series of said feed boards having a gate-closed aperture and being shiftable to direct the middlings from said first dresser to either of said conveyers.
19. In a mill, the combination of a centrifugal dresser, a set of reduction rolls, a fine middlings conveyer for delivering the middlings from said dresser to said reduction 10 rolls, a second centrifugal dresser, and a second set of reduction rolls, and a middlings conveyer for delivering the coarse middlings from said second dresser to said second set of reduction rolls, and a feed-board 15 adjacent said second dresser and shiftable to direct the middlings from said second dresser to either of said conveyers.
20. In a mill, a centrifugal dresser, a feed board to deliver the fine middlings from said dresser to a middlings conveyer, a set of reduction rollers for said middlings, a second centrifugal dresser, a middlings conveyer for said second dresser to receive the coarse middlings, and a second set of reduction rolls for said coarse middlings, said 25 feed-board being shiftable to direct the flow
- from said first dresser direct to one or the other of said conveyers and having an aperture therein through which the flow of fine middlings of the second dresser passes when the feed-board is in one position. 40
21. In a mill, the combination of two pairs of break rolls, a centrifugal dresser for each pair of break rolls, two sets of reduction rolls, a centrifugal dresser for each set of reduction rolls, means for delivering the fine middlings from the centrifugal dressers for the two pairs of break rolls directly to one set of reduction rolls, and means for delivering the coarse middlings from the centrifugal dressers for the two pairs of break rolls directly to the other set of reduction rolls. 45
22. In a mill, the combination of two pairs of break rolls, a centrifugal dresser for each pair of break rolls, two sets of reduction rolls, a centrifugal dresser for each set of reduction rolls, means for delivering the coarse middlings from the centrifugal dressers for the two pairs of break rolls directly to one set of reduction rolls, and means for delivering the scalped middlings from the last mentioned reduction rolls, together with the fine middlings from the centrifugal dressers for the two pairs of break rolls to the other set of reduction rolls. 50
